US00D607744S

(12) United States Design Patent
Laird et al.

(10) Patent No.: US D607,744 S
(45) Date of Patent: * Jan. 12, 2010

(54) FRAGRANCE BOTTLE

(75) Inventors: Treyton Laird, New York, NY (US);
Hans Dorsinville, New York, NY (US);
Elizabeth Bogert, Croton on Hudson,
NY (US); Jesse A. Chertoff, Brooklyn,
NY (US)

(73) Assignee: Gabrielle Studio, Inc., New York, NY
(US)

() Term: 14 Years

(21) Appl. No.: 29/318,865

(22) Filed: May 29, 2008

(51) LOC (9) Cl. 09-01

(52) U.S. Cl. D9/573; D9/454; D9/574

(57) CLAIM

The ornamental design for a fragrance bottle, substantially as shown and described.

DESCRIPTION

FIG. 1 is a top, front and right side perspective view of a first embodiment of a fragrance bottle showing our new design;

FIG. 2 is a front elevation view thereof, the rear elevation being identical thereto;

FIG. 3 is a side elevation view thereof, the opposite side elevation view being identical thereto;

FIG. 4 is a top plan view thereof;

FIG. 5 is a bottom plan view thereof;

FIG. 6 is a top, front and right side perspective view of a second embodiment of a fragrance bottle showing our new design;

FIG. 7 is a front elevation view thereof, the rear elevation being identical thereto;

FIG. 8 is a side elevation view thereof, the opposite side elevation view being identical thereto;

FIG. 9 is a top plan view thereof;

FIG. 10 is a bottom plan view thereof;

FIG. 11 is a top, front and right side perspective view of a second embodiment of a fragrance bottle showing our new design;

FIG. 12 is a front elevation view thereof, the rear elevation being identical thereto;

FIG. 13 is a side elevation view thereof, the opposite side elevation view being identical thereto;

FIG. 14 is a top plan view thereof; and,

FIG. 15 is a bottom plan view thereof.
